(57) **CLAIM**

The ornamental design for a slide rail, as shown and described.

DESCRIPTION

FIG. 1 is a front, left side, and top perspective view of a slide rail, showing our new design;
FIG. 2 is a front side elevational view thereof, the rear side elevational view being identical thereto;
FIG. 3 is a top plan view thereof;
FIG. 4 is a bottom plan view thereof;
FIG. 5 is an enlarged left side elevational view thereof, the right side elevational view being identical thereto;
FIG. 6 is a rear, right side, and bottom perspective view thereof;
FIG. 7 is a rear, right side, and bottom perspective view thereof, showing lower rail and ball cage with upper rail removed for clarity;
FIG. 8 is a front, left side, and top perspective view thereof, showing the upper rail in an alternate, displaced position from the lower rail; and,
FIG. 9 is a rear, right side and bottom perspective view thereof, showing the upper rail in an alternate, displaced position from the lower rail.

1 Claim, 4 Drawing Sheets
